RUG CLEANING ATTACHMENT FOR VACUUM CLEANER

Siegmund B. Holubinka, 1022 N. Main St.,
Naperville, Ill. 60540

Filed May 28, 1970, Ser. No. 33,203

Term of patent 14 years

Int. Cl. D15—05

U.S. Cl. D49—18

Fig. 1

Fig. 2

Fig. 3

Fig. 4

Fig. 5

Fig. 6

FIG. 1 is a front perspective view of a rug cleaning attachment for vacuum cleaner embodying my new design;

FIG. 2 is a front elevational view of the rug cleaning attachment;

FIG. 3 is a bottom view of the rug cleaning attachment;

FIG. 4 is a rear elevational view of the rug cleaning attachment;

FIG. 5 is a top plan view of the rug cleaning attachment; and

FIG. 6 is a side elevational view of the rug cleaning attachment, the opposite side elevation appearing as a mirror image of the side shown.

I claim:

The ornamental design for a rug cleaning attachment for vacuum cleaner, substantially as shown and described.
